UNITED STATES PATENT OFFICE.

ARCHIBALD G. JANES, OF FITZGERALD, GEORGIA.

ELEVATOR BRAKE.

Application filed February 15, 1922. Serial No. 536,833.

To all whom it may concern:

Be it known that I, ARCHIBALD G. JANES, citizen of the United States, residing at Fitzgerald, in the county of Ben Hill and 5 State of Georgia, have invented certain new and useful Improvements in an Elevator Brake, of which the following is a specification.

This invention relates to an elevator brake 10 and has for its principal object to provide means whereby an elevator may be quickly and efficiently stopped should it become uncontrollable by the ordinary means.

Another object of the invention is to provide an elevator brake which will act as a safety device being capable of being actuated at a convenient point within the elevator and necessitating only a minimum amount of exertion to actuate the same.

20 A still further object of the invention is to generally improve upon elevator brakes of this nature by providing a device which will be extremely simple and efficient in construction, reliable in operation, and well 25 adapted to the purpose for which it is designed.

With the above and numerous other objects in view as will appear as the description progresses, the invention resides in certain 30 novel features of construction and in the combination and arrangement of parts as will be herein after more fully described and claimed.

In the drawing:

35 Figure 1 is an elevation of an elevator showing my invention attached to the top thereof, a portion of the side wall of the elevator being broken away to show the interior thereof,

40 Figure 2 is a top plan of the mechanism shown in Figure 1, and

Figure 3 is a vertical section taken substantially on the line 3—3 of Figure 2.

45 Referring to the drawing in detail it will be seen that the elevator 1 may be of any conventional construction and is provided with the usual guide receiving members 2 that embrace the guides 3. This elevator may be raised and lowered in any desired 50 manner and no mechanism for this purpose has been illustrated since it does not form a part of this invention.

55 The brake mechanism has been illustrated as mounted on the top of the elevator but it is to be understood that it may be mounted on the bottom thereof or in any other con-

venient manner. In the present illustration of the invention, a pair of rock shafts 4 are journaled in the brackets 5 so as to extend parallel with the sides of the elevator 1 having the guide receiving members 2 thereon. These shafts and brackets are arranged in close proximity to the sides of the elevator. A bar 6 is positioned so as to span the distance between the rock shaft 4 and is 60 provided with journals 7 at its ends for receiving the shaft. The intermediate portion of the rod 6 is supported on a bracket 8 by means of a clamp member 9 fixed to the top thereof. Another bracket 10 is situated between the shafts 4 in alignment with the bracket 8 so that the shaft 11 may be journaled in the brackets 8 and 10. This shaft 11 extends through the bracket 10 and is provided on this end with a worm gear 70 75 80 85

13. The shafts thus far mentioned are all horizontally disposed. A vertically disposed shaft 14 is journaled in a bracket 15 carried interiorly of the elevator 1 and mounted preferably on the front wall thereof. This shaft 14 extends through the top of the elevator in the present example and is provided at its end with a worm 16 in mesh with the worm gear 13. The lower end of the shaft 14 is provided with a beveled gear 19 that meshes with a beveled gear 20 which is fixed to an operating wheel 21 suitably journaled as at 22. The shaft 14 forms the main drive shaft and the shaft 11 forms the auxiliary drive shaft. This auxiliary drive shaft 11 90 95 100 105 110 is provided with a pair of spool members 23 in which are trained the chains 24 that are adapted to be wound therein. The driven rock shafts 4 are each provided with an actuating crank 25 and an actuated crank 26. The chains 24 are attached to the terminals of the actuating cranks 25. The actuated cranks 26 are provided with suitable brake shoes 27 adapted to be brought into frictional engagement with the guides 3. It will be noted that the present illustration of the invention shows the actuating cranks depending from the rock shafts 4 while the actuated cranks 26 extend upwardly therefrom. The chains 24 are so disposed about the spools 23 as to pull the chains and rotate the actuating cranks toward each other or toward the center of the elevator thereby actuating the actuated cranks 26 away from the elevator and pushing the brake shoes 27 in frictional engagement with the guides 3. It will also be understood

that this is accomplished by rotation of the operating wheel 22 transmitting its rotation through the gear 20, gear 19, drive shaft 14, worm 16, worm gear 13, auxiliary drive shaft 11, to the spools and so as previously indicated.

Although I have described my invention with some degree of particularity it is to be understood that this has only been done by way of example and that many changes in form, proportion, and in the arrangement and combination of parts may be resorted to without departing from the spirit of this invention.

Having thus described my invention what I claim as new is:—

1. In combination, an elevator, a pair of rock shafts mounted on the elevator, actuating and actuated cranks extending from the rock shafts, brake shoes carried by the actuated cranks, chains carried by the actuating cranks, an auxiliary drive shaft journaled on the elevator, spools on the auxiliary drive

shaft over which said chains are trained, a worm gear keyed to said auxiliary drive shaft, a driven shaft suitably journaled on the elevator so as to extend therethrough and terminate interiorly thereof, and means within the elevator for rotating said drive shaft.

2. In combination, an elevator, a pair of rock shafts journaled on the elevator, actuating cranks and actuated cranks extending from the rock shafts, a rod spanning the distance between said shafts intermediate their ends and provided with journals at its ends for receiving said shafts, brake shoes carried by the actuated cranks, and means for operating the actuating cranks.

In testimony whereof I affix my signature in presence of two witnesses.

ARCHIBALD G. JANES.
